UNITED STATES PATENT OFFICE.

HERMAN A. AFFEL, OF BROOKLYN, NEW YORK, ASSIGNOR TO AMERICAN TELEPHONE AND TELEGRAPH COMPANY, A CORPORATION OF NEW YORK.

REPEATER FOR MULTIPLEX SYSTEMS.

Application filed September 26, 1919. Serial No. 326,515.

To all whom it may concern:

Be it known that I, HERMAN A. AFFEL, residing at Brooklyn, in the county of Kings and State of New York, have invented certain Improvements in Repeaters for Multiplex Systems, of which the following is a specification.

This invention relates to multiplex transmission and more particularly to repeater circuits for use in multiplex systems. One of the features of the invention resides in the provision of a repeater arrangement for a multiplex system, in which oppositely directed transmissions take place at different frequencies, the repeater circuit being so arranged that all of the transmissions in one direction will be amplified by one one-way repeater and all of the transmissions taking place in the opposite direction will be amplified by another one-way repeater.

Another feature of the invention relates to the provision of a repeater circuit in a multiplex system of the character above described, said repeater circuit being so arranged that oppositely directed transmissions will be separated by means of balancing arrangements and the separation due to balance will be further increased by a frequency separation between the oppositely directed channels.

These features, together with other features of the invention more fully hereinafter appearing, are realized by the arrangements set forth in the following description and disclosed in the accompanying drawing, the figure of which illustrates in simplified form one embodiment of the invention.

In the drawing, ML designates a main line section extending from a repeater station to a terminal multiplex carrier station, at which suitable apparatus is arranged to superpose a plurality of signals on the line. At the terminal multiplex station a common transmitting circuit TL is associated with the main line through a balanced transformer arrangement 10, while a common receiving circuit is bridged across the midpoints of the line windings of the transformer 10. In order to render the circuits TL and RL conjugate with respect to each other, the main line ML is balanced by an artificial line or network MN. L₁, L₂ and L₃ designate a plurality of low frequency signaling circuits, these circuits being associated with the common transmitting circuit

TL through transmitting channels TL₁, TL₂ and TL₃, respectively. The lines L₁, L₂ and L₃ are similarly associated with the common receiving circuit through receiving channels RL₁, RL₂ and RL₃, respectively. 60

In order to translate the low frequency signals into modulated carrier currents of different frequencies, modulators M₁, M₂ and M₃ are provided in the several transmitting channels. These modulators may be of any well-known type, but are preferably vacuum tube modulators so arranged that different carrier frequencies supplied thereto will be modulated in accordance with low frequency signals. In order to maintain a frequency separation between the several transmissions, the carrier frequencies supplied to the modulators should be different and for purposes of illustration the carrier frequencies supplied to the modulators M₁, M₂ and M₃ 75 are indicated upon the drawing as being 5,000 cycles, 8,000 cycles and 11,000 cycles, respectively. It will be understood, of course, that these frequencies are merely illustrative and that in practice any suitable frequencies may be chosen which existing conditions will warrant. Filtering arrangements TF₁, TF₂ and TF₃ are also provided for the transmitting channels, in order to maintain a frequency separation between 80 them. These filters may be either tuned circuits of any well-known type, or they may be band filters of the type disclosed in the U. S. Patents, Nos. 1,227,113 and 1,227,114, issued to George A. Campbell under date 85 of May 22, 1917. Where band filters are employed they should be so designed as to transmit a band of frequencies in the neighborhood of the carrier frequency assigned to the channel, the band being of sufficient 90 width to accommodate the frequency variation due to modulation.

In order to amplify the several carrier frequencies which are impressed upon the common transmission circuit TL, an amplifier TA is provided in said circuit TL. This amplifier may be of any well-known type, but is preferably an amplifier of the well-known vacuum tube type. A filter TF is also provided in the circuit TI₄, this filter 100 being preferably a band filter of the type disclosed in the above mentioned patents to Campbell. The filter should be so designed as to transmit a band of frequencies sufficiently wide to accommodate all of the 105 110

modulated carrier frequencies impressed upon the circuit TL .

The common receiving circuit RL includes a filter RF and an amplifier RA . The filter RF , like the filter TF , should be a filter of the Campbell type, designed to transmit a band of frequencies sufficiently wide to accommodate all of the frequencies to be transmitted to the several receiving channels. Where the system is arranged as hereinafter prescribed, so that the frequencies used for transmitting will all lie in one range, while those used for receiving will lie in another range, the filter RF will, of course, be designed to transmit a different band of frequencies from the filter TF . In this manner the separation between oppositely directed transmissions provided by balance will be supplemented by frequency separation. The amplifier RA will in general be similar to the amplifier TA and serves a similar purpose with respect to the received carrier currents.

Filters RF_1 , RF_2 and RF_3 are included in the receiving channels RL_1 , RL_2 and RL_3 , respectively. These filters may be either tuned circuits or band filters of the Campbell type, and in the latter case should be so designated as to transmit a band of frequencies in the neighborhood of the carrier frequency assigned to each receiving channel. In the case illustrated the frequencies used for receiving are in an entirely different range from the several frequencies used for transmitting and consequently the filters are designed to transmit frequencies in the neighborhood of 15,000 cycles, 18,000 cycles and 21,000 cycles, respectively. It will be understood, however, that other frequencies than those indicated may be utilized.

Detectors D_1 , D_2 and D_3 are also included in the receiving channels. These detectors may be of any well-known type, but are preferably vacuum tube detectors operating upon the homodyne principle of receiving. Consequently the detectors are supplied with unmodulated currents of the carrier frequency assigned to the channel, these frequencies being, as above stated, 15,000, 18,000 and 21,000 cycles. The unmodulated carrier currents supplied to the detectors interact with the received modulated carrier currents, so that the low frequency signals in accordance with which the received carrier currents were modulated, will appear in the output circuits of the detectors.

At the repeater station the main line ML is associated with an eastbound repeater channel EL and a westbound repeater channel WL , through a balanced transformer arrangement 20, the channel WL being connected to the midpoints of the line windings of said transformer. In order to render the two repeater channels substantially conjugate, the line ML is balanced by means

of a network N . A similar line ML' leads from the repeater station to another terminal carrier arrangement (not shown), similar to that already described. Said main line ML' is likewise associated with the east and west bound repeater channels, through a balanced transformer arrangement 20', the eastbound channel EL being connected to the midpoints of the line windings of the transformer. The channels EL and WL are rendered substantially conjugate as regards the line ML' , by means of a network N' for balancing said line.

Repeaters AE and AW are included in the lines EL and WL , respectively. These repeaters may be of any well-known type, but are preferably amplifiers of the well-known vacuum tube type, so designed as to amplify a plurality of carrying frequencies.

In order to supplement the separation between east and west bound transmissions, which is due to balance, means for permitting of frequency separation between the oppositely directed transmissions are provided. Said means comprise band filters EF and EF' on either side of the amplifier AE and band filters WF and WF' on either side of the amplifier AW . The filters EF and EF' are preferably band filters of the Campbell type, already described, and are so designed as to transmit a band of frequencies sufficiently wide to accommodate the several modulated carrier frequencies originating in the transmitting channels TL_1 , TL_2 and TL_3 . The band filters are therefore illustrated as passing a band frequency between three and thirteen thousand cycles.

The filters WF and WF' are similar to the filters EF and EF' , already described, except as to the range of frequencies transmitted. These filters are designed to transmit a band of frequencies sufficiently wide to accommodate the several modulated carrier currents received by the channels RL_1 , RL_2 and RL_3 , and, therefore for purposes of illustration these filters are indicated as transmitting a band lying between thirteen and twenty-three thousand cycles. The exact frequencies assigned to the several channels and the frequencies transmitted by the various filters may, of course, be varied as conditions require.

The operation is as follows: Low frequency signals incoming from the lines L_1 , L_2 and L_3 are transmitted into the transmitting channels TL_1 , TL_2 and TL_3 and are impressed upon the modulators M_1 , M_2 and M_3 , respectively, to modulate the carrier frequencies assigned to the several channels. The modulated carrier frequencies are then passed through the filters TF_1 , TF_2 and TF_3 and after passing into the common transmitting circuit TL are amplified by the amplifier TA , passed through the filter TF and

transmitted through the transformer 10 to the main line ML. As the transmitted modulated frequencies lie without the band passed by the filter RF, any transmitted energy impressed upon the common receiving circuit RL, due to unbalance, will be suppressed by said filter RF. After transmission over the main line ML the modulated carrier frequencies are transmitted through the transformer 20 into the eastbound channel EL. These frequencies will, of course, be prevented from being substantially diverted into the westbound channel WL, by reason of the fact that the filter WF' passes a band of frequencies lying without the range of frequencies employed for transmission in an eastbound direction. The frequencies transmitted to the eastbound repeater channel EL pass through the filter EF and are amplified by the amplifier AE. The amplified frequencies are then passed through the filter EF' and are then impressed upon the midpoints of the line windings of the transformer 20', so that half of the energy flows over the main line ML' to the distant station and the other half flows to the balancing network N. Such energy as may be impressed upon the westbound channel WL, due to unbalance, is substantially suppressed by the filter WF.

The modulated carrier currents transmitted from the distant station and incoming from the line ML', are transmitted through the transformer 20' to the westbound channel WL and passed through the filter WF to the amplifier AW. After being amplified by the amplifier AW, the amplified frequencies are passed through the filter WF' and are then impressed upon the midpoints of the line windings of the transformer 20, so that part of the energy flows to the artificial line N and part to the main line ML. Any energy impressed upon the eastbound channel EL, due to unbalance will, of course, be suppressed by the filter EF. The several frequencies transmitted over the main line ML are prevented from reacting upon the transmitting circuit TL, by means of the filter TF and consequently the frequencies flow through the filter RF into the receiving channel RL. The several frequencies are then amplified by the amplifier RA and are selected by means of the filters RF₁, RF₂ and RF₃, respectively. The modulated carrier currents received in these channels are now detected by means of the detectors D₁, D₂ and D₃ in a well-known manner and the resultant low frequency signaling currents are transmitted over the channels to the low frequency signaling lines L₁, L₂ and L₃, respectively.

While the system, as described, provides for only three signaling circuits, it will be understood that additional signaling circuits may be provided, if desired.

It will further be obvious that the general principles herein disclosed may be embodied in many other organizations widely different from those illustrated, without departing from the spirit of the invention as defined in 70 the following claims:

What is claimed is:

1. In a signaling system, a transmission line, means for transmitting signals in one direction over said line by means of currents of one frequency, and means for transmitting signals of the same kind in the opposite direction over said line by means of currents of another frequency, a one-way repeater in said line for amplifying currents of the frequency transmitted in said first mentioned direction, and a second one-way repeater for amplifying currents of the frequency transmitted in the opposite direction. 75

2. In a signaling system, a transmission line, means for transmitting simultaneously a plurality of signals over said line in one direction by means of currents of different frequencies, means for simultaneously transmitting in the opposite direction a plurality of signals by means of currents of other frequencies, one-way repeating apparatus in said line for amplifying only currents transmitted in one direction and other 90 one-way repeating apparatus in said line, for amplifying only currents transmitted in the opposite direction. 95

3. In a signaling system, a transmission line, means for simultaneously transmitting over said line in one direction a plurality of signals by means of currents of a plurality of frequencies lying within one frequency range, means for simultaneously transmitting over said line in the opposite direction a plurality of signals by means of a plurality of currents of different frequencies lying within another frequency range, repeating apparatus in said line for amplifying currents within the one frequency range, another repeating apparatus for transmitting currents lying within the other frequency range, and means for balancing said transmission line with respect to said repeating apparatus. 100 105 110 115

4. In a signaling system, a transmission line, means for simultaneously transmitting over said line a plurality of signals by means of currents of a plurality of frequencies lying within one frequency range, means for simultaneously transmitting in the opposite direction over said line a plurality of signals by means of currents of different frequencies lying with another and entirely different frequency range, a common repeater for amplifying all of the frequencies within the first mentioned range, another common repeater for amplifying all of the frequencies within the second range, and means for balancing said trans- 120 12 17

mission line with respect to said repeating apparatus.

5. In a signaling system a transmission line, means for transmitting one range of frequencies over said line in one direction, means for transmitting another and entirely different range of frequencies over said line in the opposite direction; a two-way repeater in said line comprising a circuit for transmission in one direction, and another circuit for transmission in the opposite direction; means for balancing said transmission line with respect to said repeater circuits; an amplifier in each circuit, and selective means in one of said circuits on each side of the amplifier therein, for passing the range of frequencies used in transmitting in one direction, and selective means in the other circuit on each side of the amplifier therein, for selecting the range of frequencies used in transmitting in the opposite direction.

6. In a signaling system a transmission line, means for transmitting one range of frequencies over said line in one direction, means for transmitting another and entirely different range of frequencies over said line in the opposite direction; a two-way repeater in said line, said repeater comprising a circuit for transmission in one direction, and another circuit for transmission in the opposite direction; means for balancing said transmission line with respect to said repeater circuits; an amplifier in each circuit; a band filter on each side of the amplifier in one circuit for passing the range of frequencies transmitted in one direction and suppressing the range of frequencies transmitted in the opposite direction, and a band filter on each side of the amplifier in the other circuit for freely transmitting the range of frequencies transmitted in the opposite direction, and for suppressing the frequencies transmitted in the first direction.

45. 7. In a signaling system, a transmission line over which a plurality of signals may be simultaneously transmitted in opposite directions, the frequencies used for transmitting a plurality of signals in one direction differing from the frequencies used for transmitting a corresponding plurality of signals in the opposite direction, repeating apparatus in said line comprising a circuit arrangement for transmission in one direction, and another circuit arrangement for transmission in the opposite direction, amplifying apparatus associated with each circuit arrangement, and selective means associated with one of said circuit arrangements on each side of the amplifying apparatus for passing the frequencies used in transmitting in one direction, and selective means in the other circuit arrangement on each side of the amplifying apparatus for

selecting the range of frequencies used in transmitting in the opposite direction.

8. In a signaling system, transmission line sections, one-way transmission paths interconnecting said line sections, and frequency selective means whereby frequencies transmitted in one direction over said line sections will pass over one of said paths, and whereby frequencies transmitted in the opposite direction will pass over the other of said paths.

9. In a signaling system, transmission line sections over which a plurality of signals may be simultaneously transmitted in both directions, a circuit arrangement interconnecting said line sections for transmission in one direction, another circuit arrangement interconnecting said line sections for transmission in the opposite direction, frequency selective means for selecting into one of said circuit arrangements a plurality of signals transmitted over said line sections in one direction, and preventing transmission over said circuit arrangement of signals transmitted in the opposite direction, and frequency selective means associated with the other circuit arrangement for selecting into the said circuit arrangement a plurality of signals transmitted in the opposite direction, while preventing the transmission over said circuit arrangement of signals transmitted in the said first direction.

10. In a signaling system, transmission line sections, one-way transmission paths interconnecting said line sections, one-way repeaters in each of said paths and frequency selective means in one of said paths whereby frequencies transmitted over said line sections in one direction will pass over said path to the exclusion of the other path, and frequency selective means in the other path whereby frequencies transmitted over said line sections in the opposite direction will pass over said path to the exclusion of said first mentioned path.

11. In a signaling system, transmission line sections, one-way paths interconnecting said line sections, one-way repeaters in each path, frequency selective devices in one of said paths on each side of said repeater whereby frequencies transmitted over said line sections in one direction will pass over said path to the exclusion of the other path, and frequency selective means in the other path on each side of the repeater therein whereby frequencies transmitted over said line sections in the opposite direction will pass over said path to the exclusion of said first mentioned path.

In testimony whereof, I have signed my name to this specification this 25th day of September, 1919.

HERMAN A. AFFEL.
